APPARATUS FOR DELIVERING LIQUIDS TO
RECEPTACLES

Johan Gunnar Nilsson, Appelviken, Sweden, assignor to Areaco Aktiebolag, Stockholm, Sweden, a Swedish joint-stock company

Application April 26, 1946, Serial No. 665,170.
In Sweden April 28, 1945

3 Claims. (Cl. 226—116)

1

This invention relates to apparatus for delivering liquids to receptacles such as jars, bottles or the like. More particularly, the invention relates to such apparatus comprising a filling tube and a valve adapted to close the outlet end of said tube by relative longitudinal movement of said tube and said valve and having a stem extending longitudinally through said filling tube and being provided with an air vent channel. In the use of such apparatus the receptacle can be raised into engagement with the filling tube to force same upwardly so that said filling tube is lifted from the immovable valve whereby liquid flows out of said tube and into the receptacle. Thereby air and foam will escape from the receptacle and be discharged through the hollow valve stem. When filling receptacles with certain liquids it is inconvenient to effect this discharge by suction as a violent foaming and loss of liquid will take place. On the other hand, it is desirable to remove foam that will be produced when filling the receptacle and to prevent liquid and foam entering the valve stem from flowing back when the filling operation has terminated.

It is an object of the present invention to remove said drawbacks and to make provision for said improvements.

Still another object of the invention consists in the provision of improved means for controlled venting of the receptacle in dependence on its longitudinal movement relative to the filling tube when commencing and terminating the filling operation.

With these and other objects not specifically mentioned in view, the invention consists in certain constructions and arrangements which will be hereinafter fully described and then specifically set forth in the claims hereunto appended.

The annexed drawing illustrates one form of construction of the invention.

Fig. 1 is a vertical sectional view of the apparatus;

Figs. 2 and 3 illustrate steps of operation of apparatus; and

Fig. 4 is a cross-sectional view taken on the line IV—IV of Fig. 1.

Referring to the drawing, a spout 2 is secured to an open reservoir 1 for liquid. Into the lower end of the spout 2 is slidably inserted a nozzle consisting of a tube 3 provided with a flange 24. The tube 3 forms a valve member engageable with an upwardly facing valve seat on a head 4 at the bottom end of a stem 5 which extends longitudinally through the tube 3 and spout 2.

and is provided with a central channel 6. At its upper end the stem 5 is inserted into an upright 7 which is supported by the spout 2 at posts 8 secured to said spout. The stem 5 is secured to the upright 7 by means of a U-shaped key member 9 driven into lateral slots 23 in the stem and upright.

On the upper end of the stem 5 is slidably mounted a reversing valve member 12 which is actuated by a compression spring 13 and supported by two pins 14. The pins 14 are slidably inserted into holes 29 in the upright 7 and secured to the head 15 of a sleeve 16 slidably mounted on the stem 5. The sleeve 16 is by means of a post 17 supported by the tube 3; upon which it rests under the influence of the spring 13. Into the upper end of the stem 5 is screwed a plug 18 the head 19 of which forms an abutment for the spring 13. After removal of this plug the channel 6 of the stem 5 will be accessible for cleaning, and furthermore, the stem can then, after removal of the member 9, be pulled out of the upright 7 and the sleeve 16. At its upper end the stem 5 has a pair of outlet openings 20 and a pair of suction openings 21 both pairs being spaced apart longitudinally of the stem 5 and connected to the channel 6. The reversing valve member 12 is interiorly provided with an annular groove 22 forming a suction passage and being adapted to register with the openings 21 and being connected to a flexible hose 23 which is connected to a source 10 producing a constant suction effect.

In the operation of the apparatus as illustrated the receptacle A is raised by any suitable means (not shown) to engage the flange 24 of the tube 3 and lift said tube against the action of the spring 13 while the head 4 remains immovable so that the bottom end of the tube 3 will be opened. As soon as the tube 3 commences to move upwardly it will, by means of the post 17, the sleeve 16, and the pins 14, commence to lift the reversing valve member 12 so that the suction openings 21 begin to close. Thus, during the relatively short time interval in which the bottom edge 25 of the narrow groove 22 moves upwardly across the narrow suction openings 21 the receptacle A is subjected to a suction effect creating a sub-atmospheric pressure in the receptacle. As soon as the tube 3 commences its upward movement its bottom end will be opened by moving away from the head 4 and the suction created in the receptacle A will suck liquid relatively rapidly into the receptacle to fill same partially whereby foam will be produced upon the liquid thus having been supplied to the re-

ceptacle. This action continues until the valve member 12 has been raised into the position as shown in Fig. 2 in which its groove 22 has just been brought out of communication with the opening 21 of the stem 5. Said phase of relatively violent filling operation is followed by a second phase in which liquid is allowed to flow by its own gravity into the receptacle A to fill same completely. To this end the receptacle A and, consequently, also the tube 3 and the reversing valve member 12, are elevated further. As soon as the reversing valve member 12 commences its continued upward movement from the position as shown in Fig. 2 its bottom edge 24 commences to move upwardly across the outlet opening 20 whereupon said openings will be uncovered to communicate with the atmosphere as shown in Fig. 3. Thereby air will enter the openings 20 and flow into the receptacle A to produce an atmospheric pressure therein so that the liquid will by its own gravity flow through the gradually widening opening at the bottom end of the tube 3 into the receptacle A. This additionally supplied liquid will expel foam and force same upwardly into the channel 6 and further out through the outlet openings 20. This action continues during the time interval in which the reversing valve member 12 moves into a top position and returns to the position as shown in Fig. 2. Thus, when the receptacle A is lowered the spring 13 will force the valve member 12, and consequently, also the tube 3 downwardly while liquid is still flowing by its own gravity into the receptacle A until the valve member 12 passes the position shown in Fig. 3 to close the openings 20 and re-establish the communication between the channel 6 and the suction source 10 whereby a third phase of the filling operation will commence.

In this third phase of operation the valve member 12 moves downwardly from the position as shown in Fig. 2 whereby a suction effect will again be produced in the receptacle A. Thereby foam and air present above the liquid in the top portion of the receptacle and also air having entered through the openings 20 will be sucked through the channel 6. Simultaneously liquid will be sucked into the receptacle A and further into the channel 6 so that the receptacle will have been filled up to the mouth 30 of the channel 6 when the filling operation is finished.

It will be understood that the operation described is obtained by the distance between the bottom edge 24 of the valve member 12 and the bottom edge 25 of the groove 22 being exactly equal to the distance between the top edges 26 of the suction openings 21 and the bottom edges 27 of the outlet openings 20 as clearly shown in Fig. 1. But said distances may differ slightly without disturbing the operation since the changes of air pressure in the receptacle cannot, of course, occur instantaneously even though said distances are exactly equal.

Liquid possibly remaining on the convex bottom surface of the valve head 4 after finished filling operation will flow down towards the mouth 30 of the channel 6 and be sucked up through said channel.

I claim:

1. In an apparatus for delivering liquids from a reservoir having a spout, a fixed stem extending downwardly within said spout and having at its bottom end a head forming an upwardly facing valve seat, a nozzle slidably mounted within said spout and forming a valve member engage-

able with said valve seat, a reversing valve member supported by said nozzle and being slidably longitudinally on said stem, a channel extending longitudinally in said stem and opening through said head, a suction opening and an outlet opening in said stem communicating with said channel and being spaced apart longitudinally of said stem, a suction source, a suction passage in said reversing valve member communicating with said suction source and adapted to register with said suction opening when said nozzle rests on said valve seat whereby said outlet opening is held closed by said reversing valve member, said nozzle being upon upward movement operative to raise said reversing valve member to close said suction opening and thereafter to open said outlet opening to the atmosphere, said reversing valve member being operative upon downward closing movement of said nozzle to first close said outlet opening and then to connect said suction opening with said suction passage.

2. In an apparatus for delivering liquids from a reservoir having a spout, a fixed stem extending downwardly within said spout and having at its bottom end a head forming an upwardly facing valve seat, a nozzle slidably mounted within said spout and forming a valve member engageable with said valve seat, a reversing valve member having a bottom edge and being supported by said nozzle and being slidably longitudinally on said stem, a channel extending longitudinally in said stem and opening through said head, a suction opening and an outlet opening in said stem, said openings having each a top edge and a bottom edge and communicating with said channel and being spaced apart longitudinally of said stem, a suction source, a suction passage in said reversing valve member having a bottom edge and communicating with said suction source and being adapted to register with said suction opening when said nozzle rests on said valve seat whereby said outlet opening is held closed by said reversing valve member, said nozzle being upon upward movement operative to raise said reversing valve member to close said suction opening and thereafter to open said outlet opening to the atmosphere, said reversing valve member being operative upon downward closing movement of said nozzle to first close said outlet opening and then to connect said suction opening with said suction passage, said bottom edge of said reversing valve member being movable across said outlet opening, the distance between the bottom edges of said valve member and its suction passage being equal to the distance between the top edge of said suction opening and the bottom edge of said outlet opening.

3. In an apparatus for delivering liquids from a reservoir having a spout, a fixed stem extending downwardly within said spout and having at its bottom end a head forming an upwardly facing valve seat, a nozzle slidably mounted within said spout and forming a valve member engageable with said valve seat, a reversing valve member supported by said nozzle and being slidably longitudinally on said stem, a channel extending longitudinally in said stem and opening through said head, a suction opening and an outlet opening in said stem communicating with said channel and being spaced apart longitudinally of said stem, a suction source, a suction passage in said reversing valve member communicating with said suction source and adapted to register with said suction opening when said nozzle rests on said valve seat whereby said outlet opening

let opening is held closed by said reversing valve member, said nozzle being upon upward movement operative to raise said reversing valve member to close said suction opening and thereafter to open said outlet opening to the atmosphere, said reversing valve member being operative upon downward closing movement of said nozzle to first close said outlet opening and then to connect said suction opening with said suction passage, said head having a convex bottom face enclosing the bottom end of said channel. 10
